UNITED STATES PATENT OFFICE.

HENRY CHARLES LAVINGTON, OF NEW SOUTHGATE, ENGLAND.

MACHINE FOR DRESSING LEATHER.

SPECIFICATION forming part of Letters Patent No. 730,931, dated June 16, 1903.

Application filed February 10, 1902. Serial No. 93,314. (No model.)

To all whom it may concern:

Be it known that I, HENRY CHARLES LAVINGTON, leather-dresser, of 36 Bellevue road, New Southgate, in the county of Middlesex, 5 England, have invented certain new and useful Improvements in Machines for Dressing Leather and the Like, of which the following is a specification.

This invention relates to machines for dressing leather, and especially chamois-leather skins, though it is or may be applicable for dressing like materials to leather.

The object of the invention is to better and more expeditiously remove from the leather or material under treatment such parts thereof as are not required and at the same time to secure a better surface and finish and a more even thickness than heretofore; and my invention consists in the novel construction of certain parts and in the combinations of the various parts to produce machines adapted to dress either one or both sides of the leather or materials.

A machine for dressing leather made in accordance with my invention in one form comprises a rotary drum formed of or coated with material adapted to grind or abrade and remove the superfluous surface of the leather under treatment. This drum is hereinafter referred to as the "grounding-drum." The said grounding-drum mounted on a suitable shaft and adapted to be rotated, a resilient work-pressing surface adapted to press one surface of the leather under treatment against the grounding-drum, a second rotary grounding-drum mounted on a suitable shaft and adapted to be rotated, a resilient work-pressing surface adapted to press the other surface of the leather against the said second grounding-drum, and means for bringing the said pressing-surfaces and grounding-drums in and out of working position with respect to each other, and means for traveling the leather through the machine mechanically or manually constitute the principal parts of a complete machine. I may also arrange a means for keeping the leather in tension as it passes through the machine and means for spreading out any creases in the leather before it comes against the grounding-drum.

I prefer—and it constitutes a feature of my invention—to use a rotary grounding drum

or drums made of a cork compound, preferably that technically known as "suberit" and which comprises resilient material, such as cork impregnated with emery; but I may employ drums of wood or other material. They are covered with emery powder or emery cloth or paper or the like material glued or clipped or otherwise conveniently attached thereto.

I will now describe my invention with reference to the accompanying drawings.

Figure 1 is an elevation of the rear or feed side of the machine. Fig. 2 is a section on line *a b*, Fig. 1, looking toward the left. Fig. 3 is a sectional plan of the machine, the section being taken on the line *c d*, Fig. 1; and Fig. 4 is a sectional view, on a larger scale, of the resilient rising and falling work-pressing table, showing the arrangement of the spring-tongues thereof hereinafter described. Fig. 5 is a part plan of the same on the same scale as Fig. 4. Fig. 6 is a detail elevation showing the rising and falling brush or pressing-surface for the second grounding-roller in its depressed position on this roller. Fig. 7 is a vertical section, on a larger scale, of the spring-buffer stops hereinafter described for modifying or softening the impact of the table 18 upon the drum 7 when it is raised to bring the leather against same and for regulating the application of the pressure between the table and drum. Fig. 8 is a sectional front elevation of one extremity of the perch-carrier, the section being taken through the right-hand side rail 63 on line *e f*, Fig. 2. Fig. 9 is a sectional view illustrating the modification of the side guards, rising and falling table, and tension-roller above mentioned. Figs. 10 and 11 are diagrammatic views showing modified arrangement of resilient work-pressing surfaces.

1, 2, 3, 4, and 5 are suitably-disposed standards or A-frames. 6 is the top frame of the machine, mounted on said standards.

7 is a grounding-roller mounted on the shaft 8 and running in bearings 9 10 11, formed in brackets attached to the top frame 6.

12 is a second grounding-drum mounted on the shaft 13 and running in bearings 14 15, disposed on the frames 2 and 3.

16 and 17 are tie-rods for bracing the frames 1 2 3 4 together.

18 is a rising and falling table mounted on arms 19, fixed on the rocking shaft 20 and provided with a resilient working face composed of strips of metal—such, for example, 5 as spring-steel 21 21, (see Figs. 4 and 5)—forming, as it were, a comb secured to the table-frame at 22.

23 23 are projecting pieces or tongues attached to each of the spring-fingers 21.

10 24 is an angular rib constituting a stop adapted to engage the tongues 23 and to prevent the free ends of the spring-fingers rising too far and damaging the leather.

25 is a resilient surface constituted by a 15 brush fitted with side pieces or guards 26 26, which extend down beyond the tips of the bristles, so as in the working position of the brush to depress the leather slightly and cause it to conform somewhat to the contour of the 20 grounding-roller 12 before it comes in contact with the bristles of the brush and as it leaves the same in order that the bristles may not be unduly disturbed from their normal angle or position with regard to the work and 25 prevent them trailing more than required.

27 27 are bosses secured to the top frame 6, to which are keyed guide-bars 28 28. The brush 25 is mounted on a frame 29, Figs. 2 and 6, having sleeves 30 30 31 31, adapted to 30 work on the guide-bars 28 28.

32 32 are standards adapted to carry the rocking shaft 33.

The table 18 is adapted to be raised by the treadle 34, through the connection-rod 35, pivotally attached below the table and lowered by the counterweight 42, connected to the rocking shaft 20. The brush 25 is lowered into its operative position on the drum 12 simultaneously with the raising of the table 40 18 against the grounding-drum 7 by the depression of the treadle 34. This actuates the connecting-rod 35 and rocking shaft 20 to lift the table, and the motion of the rocking shaft 20 is transmitted by lever 36, connecting-rod 45 37, lever 38, rocking shaft 33, lever 39, and connecting-rod 40 to the brush 25, so as to depress same. On releasing the treadle 34 the counterweight 42 returns the rocking shaft 20, and thus lifts the brush 25 and 50 lowers the table 18 out of contact with their respective grounding-drums and raises the treadle.

41 is a right and left handed nut for adjusting the length of the connecting-rod 40.

55 43 43, Figs. 1 and 7, are brackets attached to the under side of the table 18 and carrying adjustable spring-pressed buffers 43^a 43^a in Fig. 1, adapted to strike against stops 44 44, fixed to the frames 2 and 3 when the table 50 is raised by the treadle in such manner as to soften or regulate the impact or application of the table and resilient surface when pressing the leather against the drum 7 when the table is raised by the treadle. The buffers 65 43^a each comprise (see Fig. 7) a central spindle 45, adapted to slide in a hollow bolt 46 and pressed by a spring 47 against an inter-

nal shoulder or stop 48. The pressure of the spring is adjustable by a screw-plug 49 screwing into the bolt 46. The hollow bolt 46 has an external thread by which it can be screwed into the bracket 43 to any desired extent to adjust its position with respect to the stop 44.

50 is a nut by which the bolt 46 can be locked in position when thus adjusted.

51, Figs. 1, 2, and 9, is a right and left handed spiral brush mounted on a spindle 51^a at the table or feed side of the machine in suitable proximity to the drum 7, the spindle 51^a running in bearings 52 52, formed in 80 brackets 53 53, depending from the top frame 6. This brush serves to smooth out the creases of the leather and insure its passing with a flat even surface between the table 18 and the drum 7.

54 is the driving-shaft extending across the machine, and 55 and 56 are fast and loose pulleys thereon. From this shaft the motion is transmitted to the shaft 8 of the grounding-drum 7 by means of the pulleys 57 58 and belt 90 59 and to the shaft 13 of the drum 12 by the pulleys 60 60^a and belt 60^b. The spiral brush 51 is likewise driven from the shaft 54 by a strap 61, running over the extremity of the shaft 54 and over a pulley 62 on the brush-spindle 51^a, respectively, the diameter of the pulley 62 being such that the brush 51 is driven at a suitable speed to effect the smoothing of the leather.

63 63 are rails provided at each side of the 100 machine, on the delivery side thereof, and supported at their outer ends on standards 64. These rails (see Fig. 8) are formed of T-iron with the two flanges constituted by the cross-piece of the T arranged vertically to serve as 105 upper and lower rails for the rollers of the perch-carriage, which I will now describe. This carriage (see Figs. 2, 3, and 8) comprises two side bars 65 65, each provided with upper and lower rollers 66 66 and 66^a 66^a, adapted to run, respectively, on the upper and lower flanges of the T-rails 63. The side bars 65 65 are braced together by tie-rods 67 68. On the tie-rod 68 is mounted a pivoting frame, upon which is in turn mounted the perch-frame proper. This pivoting frame comprises two arms 69 69, bent downwardly at their inner ends and carrying at these ends rollers 70 70, adapted to run up over cam-brackets herein-after described. These arms are braced together by a tie-rod 71 and by means of a hollow sleeve 72, extending entirely across the perch-carriage, the sleeve 72 being mounted upon the tie-rod 68 of this carriage, so as to be free to turn thereon.

The perch-frame proper is mounted on the pivoting frame described in the last paragraph in such manner as to follow the pivoting motions thereof, while being nevertheless free to slide thereon to enable any desired portion of the leather to be brought under the grounding-drums and to allow the skin to be drawn through the machine in any desired position with respect to said drums. The

perch-frame proper is composed of bent arms 73 73, having hooked forward ends to receive the perch-rod, these being braced about midway of their length by a tie-rod 74 and at their rear ends by a hollow tie rod or sleeve 75, mounted on the tie-rod 71 of the pivoting-frame and free to slide thereon, for the purpose above explained. Collars 76 76 are formed in the arms 73 73, these collars being likewise free to slide on the hollow sleeve 72, but adapted to follow the turning motion of said sleeve.

To each end of the tie-rod 67 is hooked the upper end of a spring 77, the lower end of these springs being connected, respectively, to downward extensions 78 78 of the arms 69 69. These springs serve to return the pivoting frame and perch-frame proper to position when they leave the cam-brackets, about to be described. These cam-brackets 79 79 are secured to the A-frames 1 and 4, respectively, and lie inside and parallel to the rails 63 63 at the inner ends of same. They are formed at the side facing the perch-carriage with an upwardly-inclined face and at the side remote therefrom with a downwardly-inclined face, as shown, so that when the perch-carriage is run forward to pass the forward ends of the arms 73 73 to the attendant at the other or feed side of the machine to enable him to place a fresh perch therein the rollers 70 70 in running over the cam-brackets first tilt the pivoting frame and with it the arms 73 73 upward against the pull of the springs 77 to enable the arm 73, which is opposite the shaft 13 of the roller 12, to pass over the said shaft and carry the perch-rod under drum 7 and brush 51 to the attendant at the feed side of the machine, the table 18 being of course depressed and the brush 25 raised during this operation.

The operation of this machine is as follows: The grounding-drums 7 and 12 and spiral brush 51 having been set in rotation in the direction opposed to that in which the leather is drawn through the machine, by shifting the driving-belt from the loose pulley 56 onto the fast pulley 55 the attendant at the delivery side of the machine runs the empty perch-carriage forward on the rails 63 to pass the arms 73 73 of the perch-frame proper through the machine to the attendant at the feed side to a convenient position to enable him to insert a perch-rod and skin. This attendant inserts a perch-rod 80 with a skin attached thereto into the hooked ends of the arms 73. The perch-carriage is now pushed back or adjusted to bring the forward end of the skin into proper position at the delivery side of drum 12. The operator at the feed side then depresses the treadle, thus bringing the table 18 and brush 25 into working position with respect to their respective drums. The operator at the delivery side then draws the perch-carriage toward him against the action of the grounding-drum until the skin has been drawn entirely through the machine. The

treadle is now allowed to rise, and the counterweight returns the table and brush to their inoperative positions. The perch is removed from the hooked arms 73 and the empty carriage again run forward to enable the attendant at the feed side to insert a fresh perch and skin, and so on. The skin is attached to the perch-rod in the usual manner—that is to say, the perch-rod is provided with a cord running lengthwise and secured thereto through holes in the heads of the rod. The end of the skin is passed between the cord and the perch-rod and then folded back on itself and around the rod, so as to prevent its slipping out from between the cord and the perch-rod.

Referring now to Fig. 9, 81 81 are knife-edged side guards secured to frames 82, 85 mounted over the respective ends of the grounding-drums 83, these frames being carried by any suitable part of the machine-framing. The knife-edged side guards 81 extend the entire length of the drum 83 and are secured to the frame 82 at each end by means of slots 84 and bolts 85 or in any other suitable manner which will allow their adjacent edges to be adjusted toward or away from each other. 86 is a rising and falling table adapted to be operated in the same manner as the table above described or in any other convenient way to hold the leather against the grounding-drum or to release it therefrom. This table 86, however, does not come in contact with the drum and has no resilient working face, as in the previous construction, but carries a tension-roller 87 at the feed side, which when the table 86 is in the raised position holds the leather in contact with the guard 81 and in resilient contact with the surface of the grounding-drum, which exerts its abrading or dressing action thereon in the space between the knife-edges of the side guards 81. The resiliency of the contact is due to the absence of any backing under the leather at the point of abrasion. 51 is a right and left handed spiral brush arranged at the feed side of the machine, as before, for smoothing out the leather and insuring its being presented with an even surface below the grounding-drum.

It will be understood that I may employ the arrangement described with reference to Fig. 9 either alone for operating on one face of the leather or in combination with a second grounding-drum and any other suitable resilient work-pressing surface for operating on the other face of the leather. It will also be understood that instead of employing a tilting perch-carrier for enabling the perch-carrier arms to be passed through the machine to an attendant at the feed side to permit him to insert the perch-rod therein, as in the construction hereinbefore described, I may employ a non-tilting carrier. In this case the perch-carrier can be run forward on the rails into suitable proximity to the machine to permit the attendant at the feed

side to pass a perch-rod with a skin attached thereto between the drum or drums and the work-pressing surface or surfaces or device or devices coöperating therewith where 5 these are away from the drum or drums and drop it into the arms of the perch-carrier. I may also, instead of employing work-pressing surfaces constituted, respectively, by a spring-table, such as 18, and a brush, employ two 10 such tables 18 18^a, Fig. 11, or two such brushes 25 25^a, Fig. 10.

What I claim, and desire to secure by Letters Patent, is—

1. A machine for dressing leather and the 15 like, comprising the combination of a rotary grounding-drum having a surface of resilient material impregnated with emery, a resilient work-pressing surface coöperating therewith, means for rotating said drum in an opposite 20 direction to the feed of the material, and means for bringing said surface and said drum together and apart to press the material against said drum or to release the same, substantially as described.

2. A machine for dressing leather and the like, comprising the combination of a rotary grounding-drum having a surface of resilient material impregnated with emery and a work-pressing surface composed of a comb-like series of spring-tongues, coöperating with said drum, substantially as and for the purpose described.

3. A machine for dressing leather and the like, comprising the combination of a rotary 35 grounding-drum having a surface of resilient material impregnated with emery, a work-pressing surface composed of a comb-like series of spring-tongues, coöperating with said drum, means for rotating said drum in an 40 opposite direction to the feed of the material, and means for bringing said surface and drum together and apart to press the material against said drum or to release same, substantially as and for the purpose described.

4. A machine for dressing leather and the like, comprising the combination of a rotary grounding-drum, a work-pressing surface composed of a comb-like series of spring-tongues, coöperating with said drum, a stop 50 for limiting the vibration of the free ends of said tongues toward said drum, and means for bringing said pressing-surface and drum together and apart, and means for rotating said drum in an opposite direction to the feed of the material, substantially as and for the purpose described.

5. A machine for dressing leather and the like, comprising the combination of a first rotary grounding-drum having a surface of re- 60 silent material impregnated with emery, a resilient work-pressing surface coöperating therewith, to press one face of the material against said drum, a second rotary grounding-drum having a surface of resilient mate-

rial impregnated with emery, a second resilient work-pressing surface coöperating therewith to press the other face of the material

against said second drum, means for simultaneously bringing the respective drums and surfaces together and apart, and means for 70 rotating said drums in an opposite direction to the feed of the material, substantially as and for the purpose described.

6. A machine for dressing leather and the like, comprising the combination of a rotary 75 grounding-drum having a surface of resilient material impregnated with emery, a resilient work-pressing surface coöperating therewith, means for bringing said pressing-surface and drum together and apart, resilient buffer- 80 stops for receiving and regulating the impact of said pressing-surface upon said drum and means for rotating said drum in an opposite direction to the feed of the material, substantially as and for the purposes described. 85

7. A machine for dressing leather and the like, comprising the combination of a first grounding-drum, a work-pressing surface composed of a comb-like series of spring-tongues, coöperating therewith to press one 90 face of the material against said drum, a second rotary grounding-drum, a resilient brush coöperating therewith to press the opposite face of the material against said second drum, a treadle-operated set of shafts, connecting 95 rods and levers for simultaneously moving said surface and brush against their respective drums, means for returning said surface and brush away from said drums, and means for rotating said drums in an opposite direction to the feed of the material, substantially as described.

8. A machine for dressing leather and the like, comprising the combination of a rotary grounding-drum, a resilient surface coöperating therewith to press the material against said drum, means for bringing said surface and drum together and apart to press the material against the drum or release same, means for rotating the said drum in the opposite direction to the feed of the material, means for supporting the material and drawing it through the machine in contact with the grounding-drum, and means for keeping it in tension during said travel, substantially as set forth. 105 110 115

9. A machine for dressing leather and the like, comprising the combination of a rotary grounding-drum, a resilient surface coöperating therewith to press the material against 120 said drum, means for bringing said surface and drum together and apart to press the material against the drum or release same, means for rotating said drum in an opposite direction to the feed of the material, a perch to 125 which the material is attached, a perch-carrier for supporting said perch, and means for traveling said perch and carrier through the machine to draw the material through the machine in contact with the grounding-drum, 130 substantially as set forth.

10. A machine for dressing leather and the like, comprising the combination of a rotary grounding-drum, a resilient surface coöper-

ating therewith to press the material against said drum, means for bringing said surface and drum together and apart, to press the material against the drum or to release it, 5 means for rotating said drum in an opposite direction to the feed of the material, a rotary right and left handed spiral brush at the feed side of said pressing-surface, means for keeping the material in tension and means for 10 supporting the material and drawing it through the machine in contact with the grounding-drum, substantially as and for the purposes described.

11. A machine for dressing leather and the 15 like, comprising the combination of a rotary grounding-drum, a resilient surface coöperating therewith to press the material thereagainst, means for bringing said surface and drum together and apart to press the material against the drum or to release it, means for 20 rotating said drum in an opposite direction to the feed of the material, means for supporting the material and traveling it through the machine, and for returning it mechan- 25 ically through the machine to the feed side thereof.

12. In a machine for dressing leather and the like, the combination with a rotary ground- 30 ing-drum having a surface of resilient material impregnated with emery, of means for holding the work in resilient contact therewith, and means for rotating said drum in an opposite direction to the feed of the material.

13. In a machine for dressing leather and the like, the combination with a rotary ground- 35 ing-drum having a surface of resilient material impregnated with emery, of means for holding the work in resilient contact therewith, means for rotating said drum in an opposite direction to the feed of the material, 40 and means for giving said parts a relative movement to move them toward and from each other to press the material against said drum or to release the same.

In witness whereof I have hereunto signed 45 my name in the presence of two subscribing witnesses.

HENRY CHARLES LAVINGTON.
